7 Claims. (Cl. 209—121)

This invention relates to a machine for classifying thin sheets of metal or other material or other articles according to weight or for automatically separating or sorting the sheets or articles.

5 The object of the present invention is to provide a machine for automatically carrying out the various weighing, sorting and separating operations which are at present usually effected by hand and are dependent upon the skill and care 10 of the operator. The invention is particularly useful as a simple and effective means of accurately sorting thin plates or other articles into separated batches according to their weight and to enable such sorting to be arranged so that 15 selected plates or articles may be classified within certain predetermined weight limits and to enable such limits to be adjusted according to requirements. A further object is to provide a machine which may be readily set to any predetermined 20 weight and to operate within any predetermined limits without the necessity for any calculations on the part of the operator.

The present invention is characterized by a weighing device for use in sorting articles, being 25 provided with means whereby a predetermined percentage difference between the weights of approximately correctly weighing articles and incorrectly weighing articles may be maintained substantially constant throughout various 30 adjustments of the predetermined weight of article to which the apparatus can be set to operate.

Briefly a weight operated sorting machine according to one form of the present invention is characterized by means operable by the weight 35 of each of the articles being sorted for automatically selecting articles of approximately predetermined correct weight from the others, and means for selectively varying the predetermined weight to which the apparatus will respond to 40 effect such selection of articles combined with means for compensating for adjustments in the said predetermined weight to permit of a substantially constant percentage difference between the weights at which approximately correct 45 articles are sorted from the others.

In carrying one form of this invention into practice the sheets or articles are delivered one at a time onto a pan, tray or receptacle carried by a weighing machine which is preferably of 50 the beam type. The pan or receptacle is preferably inclined at an angle and provided with a movable stop against which the sheet or other article rests and which is adapted to be automatically moved at a predetermined time to release the sheet or other article for delivery to 55

one or other of a number of trays or receptacles. The sheet or article when released from the pan or receptacle of the weighing machine will be directed by a deflecting member to one of the various trays or receptacles according to its weight, and this deflecting member is automatically positioned by a weighing mechanism so that if the sheet or article is within the predetermined limits of weight it will be deflected into one tray or receptacle, if it is over weight 10 it will be deflected into a second tray or receptacle, and if it is under weight it will be deflected into a third tray or receptacle. More trays or receptacles may be provided if desired but in most cases three trays as described will be suitable. 15 Combined with the weighing apparatus is a suitable means for controlling the limits of weight of the sheets or articles over and under the correct desired weight which will be delivered to the first tray or receptacle and over and under 20 which the sheets or articles will be rejected and delivered to the second or third trays or receptacles. Means is provided for enabling the percentage weight limit to be adjusted as desired. A convenient arrangement may comprise a pen- 25 dulum device connected to and operated by the balance beam of the weighing machine. The pendulum device may be provided with a slide- able weight adapted to be raised or lowered so as to vary the effective length of the pendulum 30 and this weight may be so connected to a slider on the beam of the scale that the percentage variation in weight will remain substantially constant for any selected weight within the limits of the movement of the slider on the beam. The 35 release of the sheets or articles from the pan or receptacle of the weighing machine is effected automatically by means of a mechanism adapted to be engaged with a constantly driven shaft and adapted to actuate a cam device to operate 40 the release stop as each sheet or article is weighed. The deflector plate for directing the weighed sheets or articles to the various trays or receptacles is also actuated mechanically and is set to a number of predetermined positions 45 which will be determined by the position taken up by the beam of the weighing machine and which is also partially controlled by the pen- dulum device. An adjustable opening is pro- 50 vided through which a finger connected to the beam of the weighing machine may be inserted. If the finger passes through the opening then the deflector will be set to direct the sheets or articles into the first tray or receptacle intended to receive sheets or articles which are within 55

the desired weight limits. If however, the finger is not positioned so as to pass through this opening then the deflector will be set to direct the sheets or articles into one or other of the two trays or receptacles according to whether they are under or over the prescribed weight limits. By adjusting the size of this opening the percentage variation of weight may be set to any desired limit.

10 In order that my invention may be understood and carried into practice, I will now describe by way of example a suitable manner of carrying the invention into practice as applied to a machine for use in connection with the classifying, 15 sorting or separating of tin plate or other sheets according to weight, and with reference to the accompanying drawings in which:—

Fig. 1 is a side elevation view.
Fig. 2 is a plan view, and

20 Fig. 3 is a detail side elevation view showing an alternative method of deflecting the sorted plates to their appropriate compartments.

Fig. 4 is a detail broken side elevation view and Fig. 5 a plan view showing the controlling mechanism to a larger scale.

In the construction shown the sheets may be fed direct from the cleaning machine onto a pan 1 of the weighing machine, one method of supporting the pan being by legs and hinged links 30 at one end of the beam of a beam weighing machine and hereinafter described. The legs and pan support may be suitably strengthened by angle plates or other suitable reinforcing means. The pan is arranged at a suitable angle to enable 35 the sheets to slide down its surface and is provided with a movable stop 2 against which the sheet rests whilst being weighed. This stop as shown may be a pair of fingers (see Fig. 2) fixed on a spindle 3 rotatably supported in lugs 4 so 40 that it may be rotated through the medium of a pinion 5 fixed on it and meshing with a horizontally slidable rack 6 operated in a manner hereinafter described so as to enable the sheet to slide off the pan when the stop 2 is displaced and 45 to be directed into the correct tray or receptacle. The legs 7 supporting the pan are preferably arranged substantially parallel to the saddle 8 of the weighing machine and are formed with bosses 7a at their upper ends mounted on a transverse 50 rod 9 on which is pivoted the pan 1 or frame adapted to carry the pan, a milled nut 10 threaded on one end of the rod 9 being adapted to press together to opposed serrated edges 11 of a collar 12 and of one of the bosses 7a to clamp the pan 55 1 or frame carrying it at a selected angular position relatively to a scale beam 13. When a sheet is delivered onto the pan, it is fed over a roller 14 opposite the upper end of the pan, and this roller is free to be depressed downwards so as to operate via a link 15 a lever 16 which is fulcrumed as 60 at 17 to a convenient fixed portion of the machine and carries a suitable catch 18 so as to permit a ratchet faced clutch wheel 19 mounted upon a shaft 20 to be engaged with a corresponding ratchet faced clutch wheel 21 upon another shaft 22 which is constantly driven at a suitable speed 65 from a motor 23 and reduction gear 24. The wheel 19 is splined, feathered or mounted upon a square portion of its shaft 20 so that it may slide thereon but cannot rotate relatively to the shaft. Its engagement with the member 21 will therefore cause its shaft to be rotated by the 70 constantly rotating shaft 22. Suitable cams 25 and 26 are mounted on this shaft 20 and the rotation 75 of the shaft and cams will effect the necessary

movements to weigh and sort each sheet delivered onto the pan. When the driven shaft has almost completed a revolution or cycle a projection 27 on its ratchet faced clutch wheel 19 will engage against an inclined face 28a on a catch 28 pivotally mounted at 17a with the result that the ratchet wheel 19 will be disengaged from the corresponding ratchet wheel 21 on the driving shaft and will be brought to rest against a stop 28b on the catch 28. A small catch or spring may be 10 provided to prevent accidental movement in the reverse direction thus preventing engagement of the ratchet wheel except when required. The driven shaft and cams will now remain stationary until another sheet is fed onto the pan when a 15 fresh cycle of weighing and sorting will be effected.

5 The balance or weighing device used may be of the compound unequal-armed type. The long arm of the beam 29 may be provided with numbered graduations as shown according to the 20 weights of the sheets. A sliding counterpoise 30 is mounted on the long arm and may be moved along the graduated scale to a position corresponding to any desired weight of sheet, and 25 convenient means may be provided for fixing the sliding counterpoise in any desired position. The balance or beam 29 may have its fulcrum or knife edges 31 supported on seatings 32 on a suitable upright 33 and the weight end of the balance or 30 beam also has knife edges 34 supporting on bearings the saddle 8 having the legs 7 and a stay 35 and a rod suspended from the saddle may be connected to a suitable dash pot device 36 carried by the forked upper end of a fixed Z-shaped bracket 35 36a.

To the balance or beam is fixed above its fulcrum an L-shaped bracket 37 the free end of which is formed with a boss rotatably supporting a vertical rod 38 threaded through a suitable pendulum weight 39 which is mounted so as to slide vertically on two guide rods 40 depending from the beam 29 or its bracket 37. A milled head 41 enables the rod 38 to be rotated to simultaneously feed the weights 30 and 39 towards or away from 45 the point of fulcrum of the beam. The counterpoise weight and pendulum weight are interconnected in such a manner that when the beam 29 is at its zero position or on the point of balance when the machine is unloaded the pendulum 50 weight is located with its centre of gravity in line with the fulcrum knife edges or pivotal point of the beam. The rod 38 carries a bevel pinion 42 meshing with another one 43 on a feed screw 45 supported at one end in the bracket 37 and at its other end in a lug 44 on the beam, this feed screw being threaded through the counterpoise 30 so that simultaneously with the raising of the pendulum weight 39 the counterpoise 30 is fed towards the fulcrum of the beam.

60 The movable pendulum weight acts to control the percentage under or over weight of the selected sheets and when the sliding counterpoise weight is at its zero load position then the pendulum weight may also be at its zero position. The action is such as to give automatically the same percentage of over or under weight for any given weight of plate, the pendulum weight moving as the sliding counterpoise weight is moved along the graduated arm of the beam so as to 65 maintain the percentage constant. The amount of percentage in over and under weight will be dependent on the weight of the pendulum weight and its angular travel.

70 From the long arm of the beam is suspended a 75

- rod 46 on which is mounted a blade finger 47. The suspended rod and blade finger are free to move vertically with the movement of the beam until a sheet has been weighed. Then the cam 25 which is rotated by the driving shaft through the engagement of the ratchet wheels 19 and 21 will press against a spring loaded sliding block 48 between which and a block 49 similarly supported is loosely gripped the rod 46. If the weight of the sheet is within the percentage limit the machine has been set to, the blade finger 47 of the suspension rod will pass between suitably arranged sliding blocks 50 and 51 guided on rods 53, and no movement will be given to a sheet 10 guide or deflecting member 52 arranged so as to receive and deflect the sheet when released from the pan of the weighing machine. Under such conditions the deflecting member is located so that the sheet will be directed into a tray or 15 receptacle 59 intended to collect sheets which are of the correct weight within the prescribed percentage weight limits. Should the sheet be over the percentage weight limit the blade finger 47 will strike against one of the two sliding blocks 20 25 50 and 51 moving it so as to impart movement to a horizontal lever 54 pivoted at 55 and connected to a connecting rod 56 connected to a depending crank 57 of the sheet guide or deflector 52 so that this will be moved to a position 25 to guide or deflect the overweight sheet into a tray or receptacle 60a intended to collect the overweight sheets. If the sheet is under weight then the blade finger will strike against the other sliding block 51 and the movement imparted to 30 the sheet guide or deflector will be such as to cause the sheet to be directed into a tray or receptacle 60 intended for the collection of under weight sheets. The sheet guide or deflector may comprise a plate pivoted along one edge 52a 35 adjacent to the lower end of the pan or receptacle of the weighing machine so that when the stop thereon is moved to release the sheet from the pan or receptacle it will slide onto the sheet guide or deflector. The guide or deflector is 40 set to one of three positions according to whether the blade finger passes through the gap between the sliding blocks or whether it strikes against one or other of the sliding blocks. These positions are so arranged that the sheet will be guided or 45 deflected according to whether it is within the prescribed limits or weights or whether it is over the prescribed limits so that the sheets will be collected in separate trays or receptacles. 50
- The sliding blocks are preferably arranged so 55 that their sliding movement is in a substantially horizontal plane on the rods 53 and they carry vertical striking posts 50a and 51a to engage the lever 54. They are however, mounted so as to be adjustable in a substantially vertical direction so as to enable the gap between them to be increased or decreased. This will enable the percentage of under or over weight of the selected sheets to be adjusted to any desired extent within the limits allowed by the weight of the pendulum device. A 60 suitable means for adjusting the gap between the sliding blocks consists in mounting the rods 53 carrying them in suitable collars 62 adapted to be moved toward or away from each other, for example by means of a left and right handed screw-thread 63 adapted to be rotated by hand through the medium of a suitable hand wheel or the like and threaded through said collars which are on the ends of arms 62a sliding up and down a rod 64. The percentage under or over weight to which 65 70 75 the device is set may be indicated by means of a pointer or hand 65 suitably pivoted on a support and adapted to move over a graduated scale 66. The movement may be imparted to the hand by means of a flexible ligature 74 connected to the upper of the sliding blocks 62 and carried round a small wheel 75 fixed to the spindle 76 of the hand 65. A clock spring is provided with the said spindle to hold the ligature 74 taut.
- In a machine for use in connection with tin plate sheets, the drive for the machine can be 10 taken from the cleaning machine or further a suitable electric or other motor or from a line shaft or other suitable gearing. Suitable gearing may be employed so that the rotating parts of the weighing machine will be driven at a desired slow speed for example about 40 or 60 revolutions per minute. This speed may be greater or less if desired. 15
- The operation of the weighing and sorting machine is as follows:— 20
- A sheet is fed from the cleaning machine rollers onto the pan of the weighing machine. Under its weight the roller 14 and link 15 will move relatively to the beam of the weighing machine operating the catch 28 to enable the clutch wheels 19 and 21 to engage so that the driven shaft 20 of the weighing machine will be coupled with the rotating driving shaft 22. During the first part of the revolution of the driven shaft the sheet is weighed and when this has 30 been effected the cam 25 on the driven shaft will act upon a pusher member moving the suspension rod 46 and the blade finger 47 toward the sliding blocks 50 51 previously referred to. If the sheet is over weight the finger 47 will 35 strike against the upper block 50 and if under weight the blade finger 47 will strike against the block 51 the movement of which will be transferred by the member 54, rod 56 and crank 57 to the guide or deflector 52 so as to set it to 40 a position to direct the weighed sheet into the tray or receptacle intended to receive the over or under weight sheets. The sheet guide or deflector 52 and the suspension rod with its blade finger 47 are held in this position whilst a cam 45 26 on the driven shaft engages against and operates a lever 68 giving movement to a connecting rod 69 which is connected to a depending arm 62a of the sliding rack 6 so as to move the stop 2 on the pan or receptacle. This stop is moved 50 out of the way of the sheet on the tray or receptacle which is thus permitted to slide onto the sheet guide or deflector 52 by which it is directed into its correct tray or receptacle. If the weight of the sheet is within the prescribed weight limits 55 then the sheet guide or deflector is left in its normal or intermediate position which will be such as to deflect or guide the sheet when released from the pan or receptacle into the tray or receptacle 59 intended to collect the sheets 60 which are within the prescribed weight limits. During further revolution of the driven shaft the cams release the respective levers which are returned to their normal positions by a suitable spring 78 connected to the rod 56 and the weight 65 of the pan 1 acting through the member 6 on the rod 69 by means of meshing pinion 5. As the cycle of movement is completed the stud 27 on the ratchet clutch wheel 19 on the driven shaft travels along the deflecting surface 28a and engages the stop 28b whereby the wheel 19 is disengaged from the ratchet wheel 21 on the driving shaft. Spring 6a is provided for returning rack bar 6 to its normal position. 70
- Under usual conditions the weighing machine 75

will be weighing the same weight of sheets for long periods and it is therefore not necessary to have a quick sliding movement to the counterpoise weight 30 on the beam. The counterpoise weight may therefore be provided with a suitable slow motion device for adjusting it along the beam.

It is not necessary to have the same length of travel for the counterpoise weight and the percentage pendulum weight provided that they are arranged to move in the same ratio and to end their travel together for zero weight position and zero percentage position. If desired the pendulum weight may be adjustable independently of the counterpoise weight, for example by removing the pinions 42 and 43 and rotating the screws 38 and 45 independently.

Instead of employing a single angularly adjustable guide 52 the plates may be delivered from the pan 1 (see Fig. 3) on to an open frame 78 provided with two doors 71 and 72 pivoted at 71a and 72a respectively and normally closing the tops of two shutes 71b and 72b down which the plates above and below the correct weight are allowed to fall, the correctly weighing plates sliding over the doors 71 and 72 on to a chute 73. In this arrangement the aforementioned cam operated lever 54 would be replaced by two levers individually operated by the sliding blocks 50 and 51 and individually connected by connecting rods to cranks 71c and 72c fixed to the pivots of the doors 71 and 72 so that only one door at a time would be opened if the weighed plate is above or below correct weight.

35 I claim:—

1. In apparatus for automatically sorting articles by weight, weighing means and a sorting device operated from the weighing means, means for selectively varying the predetermined correct weight of the articles to be sorted to which the apparatus will respond to sort those articles of approximately correct weight from the others and means for adjusting the percentage weight limit, said means for selectively varying the predetermined correct weight of the article to be sorted comprising a pair of spaced abutments, an arm pivotally depending from a part of the weighing apparatus which is moved to an extent proportional to the weight of the article being sorted, a blade carried by said arm and located opposite the space between said abutments, a shaft automatically set into rotation when an article is delivered to the apparatus for weighing, means with said shaft to move said arm towards the said abutments, the said blade being adapted to engage and displace one of said abutments if the article being weighed is above predetermined correct weight, and the other abutment if the article is below correct weight, and a deflecting device adjusted to various positions by the movement of said abutments to effect sorting of the articles.

2. For use in apparatus for sorting articles by weight, a weighing device provided with means whereby a predetermined percentage difference between the weights of approximately correctly weighing articles and incorrectly weighing articles may be maintained substantially constant throughout various adjustments of the predetermined weight of article to which the apparatus can be set to operate, such weighing device comprising a balanced beam a counterpoise weight slideable on said beam, a pendulum weight adjustable towards and away from the fulcrum of the beam for compensating for variations in

the predetermined correct weight at which articles are sorted, said pendulum weight depending from the fulcrum point of the beam and means for adjusting it up and down simultaneously with linear adjustment of the counterpoise weight, feed screws threaded through said two weights, said feed screws being geared together for simultaneous rotation from a common operating member.

3. In apparatus for automatically sorting articles by weight, weighing means and a sorting device operated from the weighing means, means for selectively varying the predetermined correct weight of the articles to be sorted to which the apparatus will respond to sort those articles of approximately correct weight from the others and means for adjusting the percentage weight limit adjustable synchronously with said weighing means, an inclined pan adapted to receive the article to be weighed, a stop at the lower end of said inclined pan adapted to arrest motion of the individual articles pending a weighing operation, and means to automatically move said stop to release the article consequent upon the weighing mechanism being moved by the weight of the article.

4. Sorting apparatus comprising a beam weighing machine in which the beam has a relatively adjustable counterpoise weight and is counterbalanced by a relatively adjustable pendulum weight, a shaft and means for rotating it continuously during weighing operations, a clutch for connecting said shaft to a further shaft, means for engaging said clutch automatically consequent upon the delivery of an article on to the machine, a pan adapted to receive the article and adjustably connected to said beam, a stop at one end of said pan adapted to hold each article upon the pan pending a weighing operation, means operable from said further shaft for moving said stop to release the weighed article, and bifurcating or guiding means automatically moved to bifurcate or guide the weighed article into one of a number of delivery points automatically operated from said further shaft, and also means for varying the percentage above and below correct weight at which articles are adapted to be sorted.

5. In apparatus for sorting articles by weight, means operable by the weight of each of the articles being sorted for automatically selecting articles of approximately predetermined correct weight from the others, a pendulum weight beam, an adjustable weight thereon for selectively varying the predetermined weight to which the apparatus will respond to effect such selection of articles combined with a pendulum weight connected to said beam and adjustable for compensating for adjustments in the said predetermined weight to permit of a substantially constant percentage difference between the weights at which approximately correct articles are sorted from the others, means connecting said two weights so that they are adjusted simultaneously and synchronously and means for varying the percentage difference between the weights at which approximately correct articles are sorted from the others, said latter means comprising adjustably spaced members connected to the sorting device and adapted to individually impart a sorting operation to the sorting device and means selectively bringing said members into operation according to the weight of the article being weighed.

6. In apparatus for automatically sorting articles by weight, weighing means comprising a

pan and a balance beam, a member displaceable by the weight of each article and over which the articles are fed to the pan, means for releasing the articles from said pan, means operable by the weight of each article for delivering the said released articles to different collecting points according to whether or not the article is of predetermined average weight or above or below such weight, a rotating prime mover and a driven rotary member adapted to be connected to the rotary prime mover, means operable under the influence of the movement imparted to said displaceable member by reason of the weight of the said article to establish said connection of said prime mover and driven rotary member, an abutment movable with said beam under the influence of the weight of the article in the said pan and a pair of co-operating abutments adapted to be individually engaged by and spaced either side of the first mentioned abutment the engagement being in accordance as to whether or not the weight of the article is above or below the said average, the said second mentioned abutments being individually displaceable by the engagement therewith of the first mentioned abutment, means with said driven member to move the first mentioned abutment against either of the other abutments, and means for transmitting motion from said second mentioned abutments to said means for delivering the articles from the scale pan to said collecting point.

7. In apparatus for automatically sorting articles by weight, weighing means comprising a pan and a balance beam, a member displaceable by the weight of each article and over which the articles are fed to the pan, means for releasing the articles from said pan, means operable by the weight of each article for delivering the said released articles to different collecting points according to whether or not the article is of predetermined average weight or above or below such weight, a rotating prime mover and a driven rotary member adapted to be connected to the rotary prime mover, means operable under the influence of the movement imparted to said displaceable member by reason of the weight of the said article to establish said connection of said prime mover and driven rotary member, an abutment movable with said beam under the influence of the weight of the article in the said pan and a pair of co-operating abutments adapted to be individually engaged by and spaced either side of the first mentioned abutment the engagement being in accordance as to whether or not the weight of the article is above or below the said average, the said second mentioned abutments being individually displaceable by the engagement therewith of the first mentioned abutment, means with said driven member to move the first mentioned abutment against either of the other abutments, means to effect a fine adjustment of the spacing of said pair of abutments, an arm depending from said beam carrying said first mentioned abutment, means on said driven member to swing said arm with its said abutment towards the other said abutments, a rod and a still further abutment carried thereby and selectively engaged by all the aforementioned said abutments, said rod being operatively connected to and actuating said means for delivering the articles to different collecting points.

JOHN OLIVER POWELL.
